HOLDING COMPARTMENTS FOR PAINT TABLETS IN SHEET METAL PAINT BOXES

Hugo Liebetruth, Nuremberg, Germany, assignor
to A. Liebetruth & Co. Gesellschaft mit be-
schränkter Haftung, Nuremberg, Germany

Application February 26, 1932, Serial No. 595,362,
and in Germany January 30, 1932

3 Claims. (Cl. 41—4)

This invention relates to improvements in the holding compartments of holding frames for paint tablets, which are to be inserted into the sheet metal base of paint boxes. The known 5 paint holding compartment, to which the improvement relates, has high transverse walls, which are supported on the bottom of the base by means of their obtuse angular points, and low longitudinal walls on which supporting bars for 10 the paint tablets are bent horizontally. As the height of these longitudinal walls corresponds to the thickness of the tablets inserted from above on to the supporting bars, the upper surfaces of the paint tablets are flush or nearly flush with 15 the apex of the paint holding frame bars. The paint tablets can be offered for sale in this form in an attractive order and arrangement. The greater portion of the paint tablets, which are mostly only thin in cheap children's paint boxes, 20 is hidden and only the upper surfaces of the paint tablets are visible. However, the attractive arrangement and the secret of the particular thinness of such paint tablets do often not remain undiscovered very long, because the loosely inserted paint tablets are not secured against falling 25 out. In order to prevent the falling out and mixing up of the paint tablets already at the dispatching of the paint boxes, the space between the domed lid and the paint holding frame was 30 hitherto filled with a piece of corrugated cardboard, placed on an intermediate sheet of parchment paper, in order that the paints do not stick thereto in damp weather. Further it sometimes happens in the shop, that, when a box has been 35 opened the lower part of the box is laid onto the lid instead of the lid on the lower part. The result is, that most or all the paint tablets fall out. This often results in the box not being bought. The corrugated cardboard is mostly no longer re- 40 placed, after the paint box has been used the first time, so that thereafter mixing up of the paint tablets cannot be prevented and the box is always in disorder. Children are not capable of replacing the mixed paint tablets in their 45 proper compartments marked with the name of the paint on the frame ribs so that they remember many of the colors under wrong names.

The invention has for its object to construct the holding compartment for a paint tablet so 50 that it secures under all conditions the paint tablet loosely inserted from above against falling out. For this purpose knob or bead-like projections are formed by depressions in the transverse walls of the compartment. The paint tablet is 55 inserted with one of its short sides under one of

the projections and its other short side is pressed on to the opposite projection so that the lower edge of this other short side tends to slide off the projection. This is possible because the transverse side wall of the compartment made of very thin sheet iron and against which the one short side of the paint tablet already bears under one of the projections, yields resiliently. When the upper edge of the other short side of the paint tablet has slipped below the apex point or the apex line 60 of the other projection, it slips automatically completely under same. The paint tablet is then pushed back in this direction by the resiliency of the end wall against which it was thereby pressed. The paint tablet is then held securely 65 below the two projections so that it can no longer fall out even if the box is shaken in open condition and upside down. This secure hold is already obtained by very slightly raised projections 70 which are scarcely apparent. The projections do also not damage the paint brushes because 75 they have no sharp edges. The painting water does not cause the projections to rust because they are coated like the rest of the tablet holding frame with waterproof paint. Although the pro- 80 jections reliably hold down the paint tablets they do not prevent interchanging of the same. Con-sequently the object in view is attained in a per- 85 fect manner.

Two embodiments of the invention are illus- 85 trated by way of example in the accompanying drawing in which:—

Fig. 1 is a top perspective view of a compartment.

Fig. 2 is a cross section showing the holding 90 projections.

Fig. 3 is a top plan view of the compartment with a paint tablet inserted.

Figs. 4 to 6 show in similar views to Figs. 1 to 3 a modified form of construction with means for 95 holding down the paint tablets.

In Figs. 1 to 3 each holding compartment *a* of the holding frame *b*, *c*, *d* resting with its edge bars *b* on the base, not shown, has two transverse walls *f* which bear with their obtuse angular 100 points *g* on the base, and two low longitudinal walls *h*, from which the supporting bars *i* are bent horizontally along the edges *k*. According to the invention knob or bead-shaped projections *m* are pressed from the transverse walls *f* and 105 extend into the compartment preferably directly under the edges of the transverse frame bars *d*. As is clearly shown in Fig. 2, the projections *m* prevent the paint tablets *o* inserted thereunder from rising and therefore from falling out. The 110

projections may be provided on the longitudinal walls *h* instead of on the transverse walls *f*. The reason why the insertion of the paint tablets from above is possible in spite of the projections 5 and how these projections act as holding down means has already been explained in the introduction to which reference is here made.

According to Figs. 4 to 6 flaps *p* are stamped from the transverse walls *f* of the compartment *a*:
10 These flaps are bent up vertically to enable inserting of the paint tablets from above (Fig. 5); and then they are bent into the horizontal position. In this instance the holding frame must also be 15 enamelled on the under side so that no bare under-surfaces of the sheet iron flaps *p* rest on the paint tablets. If the surfaces were not also enamelled, the painting water would cause rust to form on the underside which would be distributed over the paint tablets by the brush when 20 brushing over the surface of the paint tablet, thus resulting in a spoiling or discoloration of the color of the paint. Apart from the necessity of enamelling the underside of the holder frame which is not necessary in the form of construction with projections, the hairs of the brushes 25 would be quickly worn by the sharp edges of the holding down flaps *p*. In spite of these apparent disadvantages protection is also sought for this form of construction.

30

I claim:—

1. A holding compartment for paint tablets, comprising in combination with the box proper, transverse walls bearing with obtuse angular points on the bottom of said box, shallow longitudinal walls bent horizontally inwards to form supporting bars, and projections for the paint tablets resting on said bars pressed inwardly from said transverse walls. 80

2. A holding compartment for paint tablets, comprising in combination with the box proper, transverse walls bearing with obtuse angular points on the bottom of said box, shallow longitudinal walls bent horizontally inwards to form supporting bars, and projections for the paint tablets resting on said bars pressed inwardly from said longitudinal walls. 85

3. A holding compartment for paint tablets, comprising in combination with the box proper, transverse walls bearing with obtuse angular points on the bottom of said box, shallow longitudinal walls bent horizontally inwards to form supporting bars, and abutment flaps stamped from said transverse walls adapted to be bent vertically upwards to allow the insertion of the paint tablet and to subsequently be bent into horizontal position on to the inserted paint tablet. 90
